UNITED STATES PATENT OFFICE.

EUGENE V. McDONALD, OF ROCHESTER, NEW YORK.

COMBINED PENCIL SHARPENER AND HOLDER.

1,210,506.

Specification of Letters Patent. Patented Jan. 2, 1917.

Application filed June 9, 1916. Serial No. 102,702.

To all whom it may concern:

Be it known that I, EUGENE V. McDONALD, a citizen of the United States, residing at Rochester, in the county of Monroe, State 5 of New York, have invented certain new and useful Improvements in Combined Pencil Sharpeners and Holders; and I do hereby declare the following to be a full, clear, and exact description of the invention, such 10 as will enable others skilled in the art to which it appertains to make and use the same.

This invention relates to a combined pencil sharpener and holder.

15 The object of the invention is to provide a device of the character named which can be utilized to sharpen a pencil when disposed in one position with respect to the pencil and further utilized to securely hold 20 the pencil in the pocket when disposed in another position on the pencil.

With the above and other objects in view the invention consists in the details of construction and in the arrangement and combination of parts to be hereinafter more 25 fully described and particularly pointed out in the appended claims.

In describing the invention in detail reference will be had to the accompanying 30 drawings wherein like characters of reference denote corresponding parts in the several views, and in which—

Figure 1 is a view of the blank from 35 which the device is formed; Fig. 2, a perspective view showing the manner of utilizing the device as a pencil sharpener, the pencil being shown in dotted lines; Fig. 3, a perspective view showing the manner of 40 utilizing the device to hold a pencil securely in the pocket, and Fig. 4, a perspective view of the device detached with the parts in the position they would occupy when used as a pencil sharpener.

Referring to the drawings A indicates the 45 blank from which the device is formed and this blank includes a body portion or strip 50 one end of which is reduced to form a tongue 11, while the other end thereof is provided with openings 12 and 13. Extending laterally from the body 10 is a V-shaped

extension 14. This extension 14 is provided with a slot 15 along one edge of which is arranged a cutter 16. Also extending laterally from the body 10 is an arm 17 provided with a V-shaped shoulder 18 adjacent its 55 free end. This arm is adapted to constitute a clip for holding the pencil in the pocket and is curved suitably for that purpose at a point adjacent its inner end. In order to increase the flexibility of the arm 60 17 the latter is bent as at 19.

In forming the device the body 10 is bent into the circular form shown in Fig. 4 and the tongue 11 engaged through the openings 12 and 13. By forcing the tongue through 65 these openings the device can be readily fitted to the desired pencil. To sharpen the pencil the device is moved to the point end and the extension 14 and arm 17 pressed together in the relation shown in Fig. 4, the 70 apex of the extension 14 being engaged against the shoulder 18. This movement of the extension 14 and arm 17 will loosen the body 10 around the pencil and permit the latter to be rotated to effect the necessary 75 sharpening.

To utilize the device to hold the pencil in the pocket said device is moved to a point adjacent the end of the pencil which is sharpened and the extension 14 and arm 17 80 having been previously released to their normal position the pencil is inserted in the pocket and the flap of the latter engaged between the pencil and the arm 17.

What is claimed is:—

85

1. A combined pencil sharpener and holder comprising a band adapted to be releasably secured around a pencil, a V-shaped lateral extension on said band having a slot 90 therein, a knife along one edge of said slot, an arm extending laterally from the band, and a shoulder on said arm against which the outer end of the extension is adapted to engage when the free ends of the extension and arm are pressed together. 95

2. A combined pencil sharpener and holder formed from a metal blank and embodying a band adapted to be releasably secured around a pencil, a V-shaped lateral extension on said band having a slot there- 100

in, a knife along one edge of said slot, an arm extending laterally from the band, and a shoulder on said arm extending laterally from the band, and a shoulder on said arm 5 against which the outer end of the extension is adapted to engage when the free ends of the extension and arm are pressed together.

In testimony whereof, I affix my signature, in the presence of two witnesses.

EUGENE V. McDONALD.
